[57] ABSTRACT

An electrical connector for the blade-type terminal of a fuse has confronting contact plates to receive the blade-type fuse terminal, an inverted U-shaped clamping member pivoted to swing about an axis transverse to the contact plates, cooperating camming parts arranged to squeeze the contact plates against the fuse terminal, and a screw at the top of the inverted "U" and arranged to bear against the top edges of the contact plates, to operate the camming parts.

FIG. 1

FIG. 2

INVENTOR
ARTHUR J. WORTH
BY *Paul S. Mack*
ATTORNEY

FUSE TERMINAL CONNECTOR

The present invention relates to connectors for blade-type terminals such as are commonly used on fuses.

An object of this invention resides in providing a new and improved connector having highly effective means for developing contact pressure between the contact plates of the connector and an inserted blade-type terminal of a cartridge fuse. A further object of the invention resides in providing a novel connector having a means for developing high contact pressure against an inserted blade-type terminal that is also effective as a positive obstruction against possible unintended shift of the terminal out of the connector but which is easily shifted out of the way when a fuse is to be removed or inserted.

A standard type of fuse is used for high currents particularly has blade-type terminals. Connectors for such terminals conventionally consist of a pair of upstanding contact plates that receive a blade-type fuse terminal. In the illustrative embodiment of the invention described in detail below terminals of this type are improved by the provision of a clamping member having sidewalls that embrace the contact plates, cooperating cams at the outside of the contact plates and on the inside of the clamp sidewalls, arranged so that pressure is built up by motion of the clamping member away from the support of the contact plates. A screw extending through the bight of the clamping member is tightened against the top edges of the contact plates for developing contact-tightening cam action. The bight is also effective for preventing a cartridge fuse from being driven out of the connector terminal as is caused by electrodynamic force in some installations. Still further, when the clamping member is released, it pivots easily about an axis perpendicular to the contact plates to a clearance position allowing removal of one fuse and insertion of another.

The nature of the invention will be more fully understood and appreciated, together with its further objects, novel features and advantages, after consideration of the following description in detail of an illustrative embodiment of the invention that appears in the annexed drawings.

In the drawings:

FIG. 1 is a side view of a connector for a blade-type terminal of a fuse, showing a portion of a fuse with its blade-type terminal in position in the connector and showing a part of the connector in phantom lines in a position that it assumes when a fuse is to be removed or another fuse is to be inserted; and

FIG. 2 is an end view of the connector of FIG. 1 as seen from the right.

Connectors of the type exemplified in the drawings normally form parts of an assembly having a pair of aligned connectors for the opposite ends of a cartridge fuse and in common use in a three-phase device. There are three pairs of such connectors side by side. In the drawings, a base member 10 of insulation carries a supporting terminal bar 12 as of copper bearing a pair of solderless connectors 14 for external circuit wiring. A pair of contact plates 16, commonly of copper, are suitably joined mechanically and electrically to terminal bar 12. The blade-type terminal T of a cartridge fuse F is received and tightly secured between contact plates 16.

A U-shaped clamping member 18 includes a bight 20 that joins sidewalls 22, 22 together. A double-headed rod 24 extends through sidewalls 22, 22 and through contact plates 16, 16. The heads of the rod or shaft 24 bear against the outside surfaces of walls 22, 22, and prevent any tendency of those sidewalls to spread. Shaft or rod 24 acts as a pivot that allows the clamping member 20 to move from the solid line position in FIG. 1 to the position represented in phantom lines, when it is necessary to insert or remove fuse F. When clamping member 20 is in the tilted position shown in phantom lines, it does not obstruct the space above the contact plates 16. The clamping member is prevented by a stop 26 from moving too far so that it remains accessible when it is to be returned to the solid-line position indicated. Moreover, stops 26 limit the motion of member 20 endwise of the fuse. This is important in some installations where there is a grounded enclosure or some other structure that the clamping member should not be permitted to touch.

Camming or wedge parts are provided, to act between sidewalls 22 of the clamping member 20 and contact plates 16. Each sidewall 22 includes an integral cam part 22a which bulges toward a related contact plate 16. Upwardly and outwardly diverging cam or ramp surfaces 26a are formed on plates 26 which bear against the nearby entire outer surface of its related contact plate 16. Cam plates 26 are made of steel in order to be more durable and harder than the copper of plates 16 in performing their cam function; and by making parts 16 and 26 separate, the ramps 26a can be formed in plates 26 by a stamping operation and yet the surface of contact plate 16 that engages terminal T remains undeformed.

Elongated slots 28 in sidewalls 22 of the clamping member 20 accommodate vertical motion of the clamping member so that camming parts 22a can move upward along ramps or cam surfaces 26a for tightening the contact plates 16 against a fuse terminal T, or downward for releasing the contact pressure.

A screw 30 is threaded through the bight of clamping member 20 and carries a pressure foot 32 for bearing against the upper diverging edge portions of contact plates 16. Screw 30 can rotate in pressure foot 32 during tightening and loosening.

When a fuse terminal has been inserted and contact pressure is to be developed, the clamping member 20 is moved to the position illustrated in solid lines in FIG. 1. Screw 30 is then tightened so as to drive pressure foot 32 against the upper edges of contact plates 16. This tightening of the screw has the effect of driving clamping member 20 upward, thereby driving cam portions 22a upward along the diverging surfaces of ramps or cam parts 26a. In the positions of the parts illustrated, cam parts 22a develop enormous pressure forcing contact plates 16 toward each other. The cam parts act on contact plates 16 most directly at a point midway between the top and bottom edges of the fuse terminal T. The buildup of the cam force tends to spread the sidewall 22 of the clamping member 20, but the double headed pin 24 prevents any such spreading motion. The shape of pressure foot 32, bearing down on the edge portions of contact plates 16 as shown, provides a small component of force acting on the contact plates to augment the contact pressure built up by the camming structure described. More important, foot 32 provides a reaction point for screw 30, and it closes off the path that terminal T sometimes tends to move because of electrodynamic forces tending to blow a fuse out of its terminal connectors under adverse conditions in some installations. When a fuse is to be removed and replaced, screw 30 is turned back enough to raise foot 32 so as to allow clamping member 20 to swing to the broken line position of FIG. 1. Stop 26 holds member 26 in a partly raised position, to be sure it will be easily accessible when it is to be returned to the solid-line position. As a matter of detail, two stops 26b are provided so that duplicate parts 26 can be used at the opposite sides of the connector.

It is evident that the novel concepts in the illustrative embodiment of the invention are subject to a latitude of change and may be utilized in various applications and therefore the invention should be construed broadly in accordance with its full spirit and scope.

I claim:

1. An electrical connector for blade-type terminals of fuses, comprising a supporting terminal bar, a pair of confronting contact plates upstanding from said terminal bar and spaced apart for receiving a blade-type terminal, and means for developing contact pressure of said contact plates against an inserted blade-type terminal, said last-named means including a U-shaped clamping member having a bight joining a pair of sidewalls between which said contact plates are received, said bight overlying the upper edges of the contact plates remote from said supporting terminal bar, cooperating cam means acting between at least one of said contact plates and the corresponding one of said sidewalls and acting primarily along an imaginary line passing approximately through the center of the fuse-terminal-engaging areas of the contact plates for increasing the clamping force of said plates as said U-shaped member is shifted in the direction away from said terminal

bar, and means for driving said bight and said upper edges of said contact plates apart for thereby forcing said contact plates toward each other.

2. An electrical connector in accordance with claim 1 wherein said sidewalls extend to a level below the space normally occupied by an inserted fuse terminal, further including means for restraining the ends of said sidewalls remote from said bight against spreading when said means for developing contact pressure is operated.

3. An electrical connector for blade-type terminals of fuses, comprising a supporting terminal bar, a pair of confronting contact plates upstanding from said terminal bar and spaced apart for receiving a blade-type terminal, and means for developing contact pressure of said contact plates against an inserted blade-type terminal, said last-named means including a U-shaped clamping member having a bight joining a pair of sidewalls between which said contact plates are received, said bight overlying the upper edges of the contact plates remote from said supporting terminal bar, cooperating cam means acting between at least one of said contact plates and the corresponding one of said sidewalls and effective to increase the clamping force of said plates as said U-shaped member is shifted in the direction away from said terminal bar, and means for driving said bight and said upper edges of said contact plates apart for thereby forcing said contact plates toward each other and a shaft extending through openings in said sidewalls and said contact plates, said shaft being formed for preventing spreading of said sidewalls away from each other and said openings accommodating displacement of said U-shaped member when said means for developing contact pressure is operated, said shaft constituting a pivot accommodating tilting motion of said U-shaped member away from its position overlying said upper edges of said contact plates for allowing removal of a blade-type terminal from the space between said contact plates.

4. An electrical connector in accordance with claim 3 wherein said sidewalls have slots for receiving said shaft, the

slots being elongated for accommodating motion of the U-shaped member toward and away from said supporting terminal bar.

5. An electrical connector in accordance with claim 3 including a fixed stop with which said U-shaped member cooperates when pivoting away from said overlying position.

6. An electrical connector in accordance with claim 1 including screw-threaded means in said bight and having a bearing foot cooperable with said upper edges of said contact plates for applying pressure to said upper edges when said contact pressure developing means is operated.

7. An electrical connector in accordance with claim 1 wherein said cam means includes a pair of formations opposite the approximate center of the fuse-terminal receiving space between said contact plates and projecting from said sidewalls inward towards said contact plates respectively, and includes upward divergent cam elements cooperable with said projecting formations, for developing contact pressure as aforesaid.

20 8. An electrical connector in accordance with claim 7 wherein said driving means includes a screw threaded through said bight and a bearing plate extending across the upper edges of said contact plates and across the space therebetween for causing contact pressure to develop as said screw is operated to drive said bight away from the upper edges of said contact plates and preventing removal of a blade-type terminal from the space between said contact plates.

30 9. An electrical connector in accordance with claim 7 including a shaft extending between portions of said sidewalls remote from said bight for preventing spreading thereof when contact pressure is developed between said contact plates and a blade-type terminal fuse, said contact plates having an opening elongated in the direction from said supporting terminal bar toward said upper edges of the contact plates, said shaft being received in said opening and being thus movable when contact pressure is being developed.
